(57) **CLAIM**

I claim the ornamental design for a portable loudspeaker, as shown and described.

DESCRIPTION

FIG. 1 is a front, right perspective view of a portable loudspeaker in accordance with the new design.

FIG. 2 is a right-side elevational view of the portable loudspeaker of FIG. 1.

FIG. 3 is a left-side elevational view of the portable loudspeaker of FIG. 1.

FIG. 4 is a front view of the portable loudspeaker of FIG. 1. FIG. 5 is a back view of the portable loudspeaker of FIG. 1. FIG. 6 is a top view of the portable loudspeaker of FIG. 1; and, FIG. 7 is a bottom view of the portable loudspeaker of FIG. 1. The dashed lines depict environmental aspects and form no part of the claimed design.
